UNITED STATES PATENT OFFICE

HUGO E. ENDERS, OF BELLEVILLE, NEW JERSEY, ASSIGNOR TO MONROE CALCULATING MACHINE COMPANY, OF ORANGE, NEW JERSEY, A CORPORATION OF DELAWARE

REGISTEE

Application filed August 8, 1929. Serial No. 384,338.

The invention has relation to means for preventing simultaneous depression of adjacent keys of registers, having for an object certain improvements therein, and it consists in the novel construction and combination of parts as set forth in the appended claims.

In the accompanying drawings illustrating certain embodiments of the invention,

Figure 1 is a side view of the invention as applied;

Figure 2 is a similar view showing a key depressed and the adjacent keys locked;

Figure 3 is a side view of a modification;

Figure 4 is a view thereof similar to Figure 2; and

Fig. 5 is a view of a key and locking strip, taken transversely of the strip.

In these drawings the numeral 18 designates digital keys of a column, there being usually a plurality of such columns, the stems of the keys being each provided with a shoulder 2, under which a locking strip common to each column of keys is adapted to be slid to engage, the depression of any key of a column, causing the locking strip to be slid under the shoulders of the two keys adjacent thereto to prevent depression thereof simultaneously with the first named key.

The locking strips are each provided with a longitudinal series of cam rises or projections 4 located between alternate couples of keys of the column, low neck-portions 5 of the strip connecting said cam rises or projections, being located between adjacent keys of said alternate couples.

Each projection 4 of the locking strip has two cam edges 6 inclined oppositely so that upon depression of any digital key of a column, the shoulder 2 thereof will engage one or the other of said cam edges and will cam the locking strip in one or the other direction. As shown, alternate keys engage similarly inclined cam edges of the projections and adjacent keys engage oppositely inclined cam edges.

In the form of the invention shown in Figures 1 and 2 of the drawings, the oppositely inclined cam edges of each projection are continued upwardly until they meet, and the

pointed portions of these projections are located above the shoulders 2 of the keys, so that when a key is depressed, these upper pointed portions of the cam projections will be cammed against and under the shoulders of the two keys adjacent thereto.

In the other form of the invention shown in Figures 3 and 4 of the drawings, the oppositely inclined cam edges 6' of each projection are connected by a flattened upper edge 7 of each projection, or in other words, the upper pointed portions of the projections are cut off or omitted. In this form of the invention upon depression of any key of a column and engagement of a cam edge of one of the projections, the locking strip will be moved to cause the top edges of the projections to be moved under the shoulders 2' of the two keys adjacent thereto to hold said adjacent keys solidly in raised position. Upon release of the key, the locking strip is returned to normal centralized position by means of a spring.

In the first form of the invention, a retraction spring for the locking strip is not needed, inasmuch as in a succeeding depression of any other key of the column, the locking strip will either not need to be and will not be moved reversely, or the locking strip will be moved reversely to prevent simultaneous depression of adjacent keys, as will be noted by an inspection of Figure 2.

I claim:

1. In a register having a column of keys, means including oppositely inclined cams arranged to alternate with successive pairs of keys for preventing simultaneous depression of any two adjacent keys.

2. In a register having a column of keys the stems of which are provided with shoulders, means including a locking strip and oppositely inclined cams arranged to alternate with successive pairs of keys and movable under said shoulders for preventing simultaneous depression of adjacent keys.

3. In a register having a column of keys, means for preventing simultaneous depression of any two adjacent keys including a locking strip common to the column and hav-

ing oppositely inclined cams arranged to alternate with successive pairs of keys.

4. In a register having a column of keys, means for preventing simultaneous depression of adjacent keys including a locking strip common to the column and having spaced projections provided each with oppositely inclined cam edges arranged to alternate with successive pairs of keys, the stems of the keys having shoulders adapted to engage said cam edges.

In testimony whereof I affix my signature.
HUGO E. ENDERS.
